BREAST OF PLOW

Shinjiro Takakita, Shoichi Takakita, Minoru Takakita, Tsutomu Takakita, and Akira Takakita, Nabari-cho, Nakagun, Mieken, Japan

Application November 26, 1954, Serial No. 471,472

3 Claims. (Cl. 97—123)

This invention relates to plows and more specifically to the mouldboards or, as they are sometimes designated, the breasts thereof. The invention is of the class of plows disclosed in our copending application Serial No. 304,662, filed August 15, 1952.

An important object of the present invention is to provide a ribbed mouldboard having spaced-apart flangeless ribs which are substantially flat in transverse section at their lower end portions and curved in transverse section at their upper end portions to provide an especially effective ribbed mouldboard with the ribs thereof of more simple construction than those disclosed in our copending application referred to above.

Another important object is to provide a ribbed mouldboard comprising spaced-apart flexible metallic ribs, capable of angular adjustment so that the mouldboard may be warped as a whole and the ribs assume stepped positions at their upper portions, and which ribs are manipulated by angularity adjusting means of simple construction, differing from the means, disclosed in our aforementioned copending application, for angular adjustment of the ribs of that application.

A further important object is to provide a mouldboard as described which causes soil, dislodged by the plow-share to move upwardly along the mouldboard and not simply fan therefrom along the lower longitudinal edges of the mouldboard.

Additionally, an important object is to provide a mouldboard as detailed, in which the upper end portions of the ribs will increase, when properly manipulated, in angularity relative to the lower portions thereof so that there will be provided a stepped upper assembly of transversely curved ribs to cause effective breaking up of the clods travelling up the mouldboard with the loose soil and the resultant material will not scatter but will be turned over and deposited in the most effective manner for desirable plowing results.

Other objects and advantages of the invention will be apparent during the course of the following detailed description of the invention, taken in connection with the accompanying drawings, forming a portion of this disclosure and in which drawings:

Fig. 1 is a bottom plan of one form of the mouldboard.

Fig. 2 is a vertical longitudinal section thereof, substantially on the line A—B of Fig. 1.

Fig. 3 is a transverse section of the lower portion of one of the similar ribs of the mouldboard, substantially on the line C—D of Fig. 1.

Fig. 4 is a transverse section of the rib referred to above, substantially on the line E—F of Fig. 1.

Fig. 5 is a bottom plan of a second form of the mouldboard.

Fig. 6 is a vertical longitudinal section thereof, substantially on the line G—H of Fig. 5.

Fig. 7 is a side view of a plow frame upon which the mouldboard of Figs. 1—4 is mounted.

Fig. 8 is a top plan of the showing in Fig. 7 but with the frame partly in horizontal section.

2

Fig. 9 is a perspective view of the mouldboard of Figs. 1—4, 7 and 8 attached to a plow frame, shown mostly in horizontal section.

In the drawings, wherein for the purpose of illustration are shown two forms of the invention, the mouldboard or breast A' includes a plurality of elongated, spaced-apart ribs 3 of springy preferably metallic material, as steel, each rib having a substantially flat surface or outer face at its lower portion 1 merging into a curved surface, being outwardly transversely curved, at the upper portion 2, with the curvature shown by way of example in Fig. 4. The ribs are closely spaced apart. Each rib 3 is provided with first mounting means at its lower end for movable attachment of the rib to a plowshare 24 by way of a plate 5 secured to the plowshare and having a rearwardly projecting end flange 6 substantially normal to the share body. The means is shown as a relatively broad hook 4 (for example, of a width substantially one-half the width of the rib), preferably of J-shape in longitudinal section, which is firmly secured to the rib, in any approved manner, as by welding. The hook 4 projects beyond the end of the rib and is adapted to hook into one of a plurality of spaced-apart slots 7 carried by the flange 6. The hook 4 has a slightly loose fit in its slot 7, and the hook provides a hinge with its pivotal axis substantially paralleling the upper edge of the plowshare so that the rib 3 may freely rise and fall to a limited extent. At its upper end, each rib is provided with a rearwardly-extending flange 8 fixedly supporting a lug or projection 9 adapted to have a sliding fit in any one of a plurality of spaced-apart openings 11 in an elongated plate 10, which plate is provided with an elongated slot 10'. Means to detachably secure the lugs 9 against accidental removal from their associated openings 11 in the plate 10, may be cotterpins 12 extending through suitable openings in the free end portions of the lugs.

The slot 10' is adapted to receive the bill portion of a hook 13 mounted upon the upwardly-extending portion or post of the plow frame 23, as by the bracket 36.

Means for manipulating or operating the mouldboard is preferably substantially similar to that disclosed in our copending application referred to above and comprise an elongated handle 25 extending along, but spaced from, the post of the frame 23 and limited in movement at its upper end portion 25' by a bracket 30 carried by the post and provided with a slot (shown in Fig. 8) through which the end portion 25' loosely extends. An inwardly-extending projection 31, extending transversely into the slot, provides two shoulders 32 and 32' for selective abutment of the portion 25' thereagainst, with spaces between the shoulders and the end walls of the slot. Additionally, there is an intermediate space 34 between the projection 31 and the facing side wall of the slot to accommodate the end portion 25' so the latter may be slid along this space 34 or may abut the projection 31. The lower end portion of the handle 25 extends substantially normal to the upper end portion thereof through a suitable bore in the base of the frame 23, and is provided, at its free end, with means for attachment to the flange 6. The means may comprise a lug 27 secured to the plate 5 to extend substantially vertically downwardly and provided with an opening to receive the screw-threaded free end of lower end portion of the handle 25 to project forwardly therefrom and receive a suitable nut 29. It is preferred that the sole 22 attached to the base of the frame 23 be provided with an upwardly-extending projection 28 having an opening to receive a part of the free end of the lower portion of the handle 25 and disposed between the lug 27 and base of the frame. The sole 22 is provided with a forwardly-extending stub 35 to receive the under portion 24' of the share 24. Oscil-

lation of the handle 25 will oscillate the share with consequent movement of the mouldboard.

The mouldboard B' of Figs. 5 and 6 and its association with a plow and plowshare differ from the mouldboard A' only in the first mounting means for movably attaching the lower portions of the ribs 18 to the plowshare, by way of a plate 14, somewhat like the plate 5, attached to the plowshare. The plate 14 has a flange 16 somewhat like the flange 6 but is also provided with a downturned portion 17' extending from the flange 16 and substantially paralleling the body of the plate 14. This body is provided with a nut-accommodating opening 19, larger in diameter than the outer diameter of a nut 20 to be described, and the portion 17' is provided with a bolt shank-accommodating opening 19' and the axis of the two openings 19 and 19' being coincident. To the rearward side of the lower portion of each rib 18 is fixedly secured, as by conventional welding, a nut 20 which extends freely in the opening 19 with up-and-down play and, through the opening 19' freely extends the shank 21 of a bolt with the screw-threaded end portion of the shank retained by the nut and the head 21' outwardly of the portion 17' and being of greater diameter than that of the opening 19' whereby the rib 18 and portion 17' are detachably secured together. In effect, the construction disclosed provides a hinge, functioning as does the hinge just mentioned.

The ribs of our mouldboards do not rotate as a whole. They are adapted to warp or twist particularly at their upper end portions while the outer surfaces of their lower portions will remain in nearly the same plane, with the warp or twist very slight. As a result, the soil which is penetrated and plowed up by the share 24 and deposited upon the lower portions of the ribs will travel up the ribs and be broken up, turned and dropped by the upper portions of the ribs when transversely warped and disposed in stepped relation.

Various changes may be made to the forms of the invention herein shown and described without departing from the spirit of the invention or scope of the claims. 40

What is claimed is:

1. In combination with a plow frame, an upwardly-extending plowshare pivotally mounted upon a lower portion of said plow frame, and means for manually 45 rotating said plowshare, a mouldboard comprising a plu-

rality of spaced-apart upwardly-extending ribs of flexible material, normally disposed in substantial parallelism, first mounting means for each rib movably mounting said ribs at their lower portions upon said plowshare to extend upwardly and away therefrom and move in unison with rotative movements of said plowshare, and second mounting means for mounting the upper portions of said ribs upon said plow frame to warp transversely in unison upon movement of said lower portions and to be disposed in stepped relation, one upper portion with respect to the next adjacent upper portion, comprising a lug extending from each of said upper portions, an elongated plate provided with a plurality of spaced-apart openings to receive each lug and an elongated slot, and said second mounting means also including means to detachably secure said lugs to said plate, and a member having a portion extending into said slot for sliding movement along said slot and having another portion fixedly secured to said frame.

2. The combination according to claim 1 characterized in that the first mounting means comprises a broad hook rigidly secured to and projecting outwardly from the lower face of the lower end of each lower portion and a rearwardly and downwardly extending flange carried by said plowshare, forming substantially a right-angle with said plowshare, and provided with a plurality of spaced-apart slots receiving the hooks for swinging movement in said slots.

3. The combination according to claim 1 characterized in that the first mounting means comprises an elongated member detachably secured to the lower end of said lower portion and provided with a head at its outer end, and a flange carried by said plow-share and provided with a plurality of spaced-apart openings to freely receive the members, each opening being of less diameter than any of said heads, said flange being disposed between said heads and rib.
